US00D479576S

(12) **United States Design Patent**
Wright

(10) Patent No.: **US D479,576 S**
(45) Date of Patent: ** Sep. 9, 2003

(54) **VALVE MANIFOLD FOR ACTUATOR SYSTEM**

D366,928 S * 2/1996 Itafuji D23/233
D367,516 S * 2/1996 Itafuji D23/233
D368,130 S * 3/1996 Itafuji D23/233
D368,298 S * 3/1996 Miller et al. D23/233
D379,844 S * 6/1997 Itafuji D23/233
D427,284 S * 6/2000 Sato et al. D23/233

(75) Inventor: **John J. Wright**, Rye, NY (US)

* cited by examiner

(73) Assignee: **Marine and Industrial Hydraulics, Inc.**, Mamaroneck, NY (US)

(**) Term: **14 Years**

Primary Examiner—Nelson C. Holtje

(21) Appl. No.: **29/170,516**

(74) Attorney, Agent, or Firm—Collard & Roe, P.C.

(22) Filed: **Nov. 7, 2002**

(57) **CLAIM**

(51) LOC (7) Cl. **23-01**

The ornamental design for a valve manifold for actuator system, as shown and described.

(52) U.S. Cl. **D23/233**

DESCRIPTION

(58) Field of Search **D23/233-237,**

D23/244-249; D15/199; 137/554, 557, 560, 624, 882, 884; 4/304; 251/219, 129.04, 331, 15
